CANDLESTICK HOLDER

Rolla P. Le Baron, 1426 S. Vine St., Denver, Colo.

Filed Feb. 13, 1961, Ser. No. 63,909

Term of patent 7 years

(Cl. D48—2)

FIG. 1.

FIG. 2.

FIG. 3.

FIG. 4.

FIG. 5.

FIG. 6.

FIG. 7.

FIG. 8.

FIG. 9.

FIGURE 1 is a perspective view looking downwardly from the front at the candlestick holder, which shows my new design;

FIGURE 2 is a front elevational view thereof;

FIGURE 3 is a bottom plan view thereof;

FIGURE 4 is a fragmentary sectional view taken along line 4—4 of FIGURE 3;

FIGURES 5, 6 and 7 are top plan views, thereof, respectively showing the holders in alternate adjustable positions;

FIGURE 8 is a modified form of the holder shown in FIGURE 1; and

FIGURE 9 is a further modified form of the holder shown in FIGURE 1.

I claim:

The ornamental design for a candlestick holder, as shown and described.
